ELECTROPNEUMATIC SOUND REPRODUCER

William C. Eaves, Elyria, Ohio, assignor to Eaves Sound Projectors, Inc., New York, N. Y., a corporation of Delaware

Application July 25, 1942, Serial No. 452,269

9 Claims. (Cl. 179—108)

1

This invention relates to sound producing apparatus and more particularly to apparatus of the type wherein a fluid stream is modulated to generate sound waves.

One of the objects of the present invention is to provide novel means for modulating a stream or current of expansible fluid so as to impart sound producing characteristics thereto.

Another object is to provide a novel modulating valve for a sound head of the air flow type and a novel voice coil arrangement for actuating said valve.

A further object is to provide a novel means for mounting and controlling the operation of the movable grid of the modulating valve of an air head.

Still another object is to provide the above means with novel apparatus for counter-balancing the effect on the movable grid of the pressure of the fluid stream.

A still further object is to provide a novel grid valve for a sound head of the air flow type, said valve being so constructed that angular oscillation of the movable grid thereof about an axis parallel to and centrally disposed relative to the air stream is adapted to produce the desired modulation of said stream.

Still another object is to provide novel means for mounting the above valve to facilitate the adjustment and assembly thereof.

A still further object is to provide a novel sound producing apparatus of the air flow type adapted to reproduce and amplify speech and music to render the latter audible for a great distance without any appreciable diminution of the fidelity of reproduction.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a sectional view taken in a vertical plane through the axis of one type of sound head embodying the present invention;

Fig. 2 is a top plan view of the modulating valve and voice coil assembly of the sound head of Fig. 1;

2

Fig. 3 is a sectional view taken substantially along line 3—3 of Fig. 1;

Fig. 4 is a sectional view, with parts broken away, taken in a vertical plane along the axis of a sound head embodying another form of the present invention; and

Figs. 5 and 6 are sectional views similar to Fig. 1 of sound heads embodying modified forms of the invention.

Referring to Fig. 1, the novel sound head illustrated therein comprises a cup-shaped casing 29 provided with a flanged upper end to which is secured a cover plate 21, the latter having mounted thereon a suitable sound propagating device, such as an exponential horn 22, and being provided with a central recess 23 which connects said horn with the casing interior. Rigidly mounted in a vertical plane in said casing is a permanent magnet 24 which has poles 24a thereon of adjoining plate 21, said poles preferably terminating on opposite sides of recess 23 with the ends thereof curved and in approximate alignment with said recess. A hollow, cylindrical member 25 of suitable magnetic material, having an enlarged externally threaded base portion 25a, is centrally mounted in casing 20, preferably by having said base portion threaded into a recess 26 provided in the base of magnet 24. The upper end of member 25 is located between the ends of poles 24a, being concentric therewith and spaced only a short distance therefrom to provide a path of decreased reluctance for the flow of magnetic flux between said poles. An externally threaded lock nut 26b may be threaded into recess 26 to engage the lower face of member 25 in order to fix the latter against inadvertent angular displacement.

The interior of member 25 serves as a fluid chamber and air under pressure is admitted thereto through a suitable inlet conduit 27 which is preferably flexible and which, in the form illustrated, connects at one end with said member and at the other end with a source of compressed air (not shown). The latter may be a pump disposed some distance from the sound head, in which event it will be desirable to provide a valve (not shown) in conduit 27 adjacent casing 20, said valve being adapted to close said conduit to maintain a line pressure above atmospheric therein when the sound head actuating means is inoperative.

To produce sound waves in horn 22, the air flow into said horn from member 25 is modulated by a novel grid valve arrangement disposed at the upper end of said member in the path of the air

stream as the latter enters the horn. In the form illustrated, said valve means comprise a circular, stationary grid 28, secured to the upper end of member 25, for example, by screws 25b, and provided with a plurality of radial slots 28a spaced equally around the center of said grid (Fig. 3). Mounted for oscillation relative to said grid in a manner more fully described hereafter is an inverted cup-shaped grid member 29, 30 comprising a disc 29 parallel to said grid and spaced a slight distance therefrom and a cylindrical wall 30 depending from said disc to surround the upper end of member 25 in the air gap between said member and the ends of magnet poles 24a. For facilitating the winding of a voice coil on member 29, 30 in a manner more fully described hereinafter, wall 30 preferably has the lower end thereof projecting beyond the lower edges of poles 24a, said projecting portion being flared outwardly to provide a widened base edge 30a which has a groove 30b formed therein. Disc 29 constitutes the rotary grid of the modulating valve, being provided with a plurality of radial slots 29a (Fig. 2) adapted for cooperation with slots 28a for the purpose of controlling the total port area available for air flow out of member 25. Variations in this port area effected by movement of grid 29 relative to grid 28 modulate the air stream so that by suitably controlling the oscillation of grid 29 a desired wave frequency within the audible range may be imparted to said stream.

In order to reinforce disc or grid 29, which is relatively thin, and prevent buckling at the center thereof, it is preferable to provide a plurality of radial ribs 29b in the upper face of said grid at predetermined points between slots 29a, four such ribs being shown in the illustrated embodiment (Figs. 1 and 2). As shown, said ribs decrease in height as the same approach the center of said grid and are preferably connected at the outer ends thereof to an annular ridge or flange 29c formed in the upper face of said grid between the periphery thereof and the outer ends of slots 29a.

In order to mount grid member 29, 30 for oscillatory movement relative to grid 28, a stub shaft 31 is secured at the upper end thereof to the center of grid 29, for example, by a press fit or by being soldered thereto. Shaft 31 projects downwardly through a recess 32 in the center of grid 28, and the walls of said recess are adapted to serve as a journal therefor. Rigidly secured to the lower end of shaft 31 is a torsion rod 33 which projects downwardly through the center of member 25 and is fixed at its lower end to the central portion of a diaphragm 34 by suitable means, such as a tapered and threaded split chuck 37 mounted on said diaphragm and a tapered nut 38 threaded on said chuck. To dampen and substantially eliminate resonant vibrations in torsion rod 33 in a direction perpendicular to the length thereof, it is preferable to surround said rod with a suitable sheath 33a of non-resonant material, such as a strip of radio wire spaghetti which extends from chuck 37 to the lower end of shaft 31. Diaphragm 34 is held in fluid-tight engagement with a shoulder 39 formed in base portion 25a of member 25 by an annular member 35, which engages the edges of said diaphragm and is in turn secured to shoulder 39 by screws 36, thereby sealing the lower end of said member. The effective area of diaphragm 34 is slightly greater than the area of grid 29 so that said diaphragm

acts through rod 33 to counter-balance the force applied by the fluid in chamber 25 on grid 29 and tends to urge the latter grid into contact with grid 28.

To overcome in part the pressure exerted by diaphragm 34 on grid 29 and permit the latter to assume an operative position wherein it is spaced a short distance from the upper face of grid 28 and also to control this axial spatial relation between the grids, novel adjustable control means are provided for exerting an upward pressure on diaphragm 34. As shown said control means comprise a hollow casing or cylinder 40 threaded into a recess 41 in the lower end of casing 20, the latter being provided with an inwardly projecting cup-shaped portion 20a at the upper end of which said recess is formed. As a result, cylinder 40 has the lower end thereof above the bottom surface of housing 20. Cylinder 40 extends vertically upward through recess 41 in the direction of diaphragm 34 and a piston 42 is slidably mounted in said cylinder, said piston having a rod 43 fixed to or formed with the upper face thereof and extending through a recess in the upper end of said cylinder. The tip 43a of said rod, which is adapted to engage the lower end of nut 38, is preferably formed of a non-resonant material, such as hard rubber. Engaging piston 42 to apply an upward yielding force thereto is a spring 44 disposed between said piston and a plug or screw 45 threaded into the lower end of cylinder 40. The pressure applied by said spring against diaphragm 34 may be controlled by axial adjustment of plug 45 relative to said cylinder or by axial adjustment of said cylinder relative to housing 20. To prevent inadvertent movement of the cylinder, a lock nut 40a is preferably screwed on the threaded shank of said cylinder to engage the face of the upper end of indented portion 20a.

In order to actuate movable grid 29 for pivotal vibratory movement about the axis of torsion rod 33 in accordance with electric current undulations produced in a conductor by a source of sound, a voice coil 46, which constitutes the conductor, is wound in a novel manner on grid member 29, 30. In the form shown, coil 46 comprises horizontal portions 46a and 46b (Figs. 2 and 3) which extend across the upper and lower ends, respectively, of said grid member, and portions 46c which connect said horizontal portions and extend vertically along the sides of wall 30 in the air gap between poles 24a and the periphery of said wall. Upper portions 46a of the windings are preferably directed across the face of grid 29 in arcuate paths between the outer edge of said grid and annular ridge 29c, thereby avoiding slots 29a. For purposes of clarity, the windings are somewhat diagrammatically shown in Figs. 2 and 3, it being understood that actually vertical portions 46c of successive windings are in contact with each other, providing a greater number of windings than is illustrated. Lower horizontal portions 46b of the windings (Fig. 3) are disposed in groove 30b in the divergent lower edge 30a of wall 30. It is preferable to secure portions 46a and 46b in operative position relative to each other and to member 29 and 30, for example, by embedding said portions in a suitable insulating compound having adhesive properties, said compound being solid at the temperatures to which the voice coil windings are raised during operation of the sound head and being applied to

said windings after the latter are operatively positioned on said member.

To modulate the air stream flowing through grid valve 28, 29 in accordance with the current undulations in coil 46 so as to reproduce with true fidelity the sound waves which initiated said undulations, slots or ports 28a and 29a are so designed that the degree of opening thereof will be directly proportional to the angular displacement of grid 29 relative to grid 28. One arrangement for achieving this result is shown in Figs. 2 and 3 wherein the slots in each of the grids are similar in shape and disposed in a like relation to the grid area, the side walls of each slot being radial and the end walls concentric with respect to the axis of rotation of grid 29. To obtain a maximum degree of fidelity in sound reproduction, it is desirable to restrict the throat of horn 22 to a cross-sectional area equal to the total port area of grid valve 28, 29 and to have this horn portion of minimum area located close to said valve.

In operation, air at a pressure exceeding atmospheric is admitted into chamber 25 through conduit 27 and flows in a stream from said chamber through grid valve 28, 29 into horn 22. The un-modulated electrical current in coil 46, when the latter is energized, provides a magnetic torque which, together with rod 33 and the air stream, act to establish a neutral position for grid 29 relative to grid 28, said grids being assembled so that in this equilibrium or neutral operative position, ports 28a and 29a are approximately half open. Current modulations in voice coil 46 cause grid 29 to rotate relative to grid 28, thereby modulating the air stream and generating sound waves therein in accordance with the current modulations. It is to be noted that assembly and adjustment of the sound head are greatly facilitated in the above-described structure since grid member 29, 30, grid 28, and diaphragm 34 can be operatively mounted on member 25 and adjusted relative to each other before the latter member is threaded into operative position in magnet 24. The novel construction of the sound head permits independent radial and axial adjustments of grid 29 relative to grid 28 and permits angular adjustment of member 25 relative to magnet poles 24a. Cylinder and piston mechanism 40, 43 provides a ready and simple means for controlling the axial adjustment of grid 29 relative to grid 28 after the unit has been assembled.

It is to be understood that the movable grid may be mounted on the high pressure side of the valve, for example, as shown in Fig. 4, wherein a stationary grid 50 is secured between horn 22 and cover plate 21 and a movable cup-shaped grid member 51, 52, comprising grid 51 and cylindrical wall 52, is mounted between the upper, open end of member 25 and grid 50. Member 51, 52 is like member 29, 30 of the above-described embodiment except that ribs 51b thereof are preferably located on the high pressure side of movable grid 51. It is to be understood that in this and the following views the voice coil is wound on the movable grid member as described in detail above and illustrated in Figs. 2 and 3.

Means for mounting grid member 51, 52, for angular oscillation are provided and, in the form illustrated, comprise a jewel bearing 53 of the type well-known in the watchmakers' art, said bearing having the journal thereof located centrally in the lower face of grid 50 and the pivotal portion carried by a member 54 mounted in the center of grid 51 and rigidly secured to the latter, 75

for example, by a press fit. The lower end of member 54 is operatively mounted in the same manner as stub shaft 31 of the embodiment of Fig. 1, being connected to torsion rod 33, which, in turn, is preferably connected to a diaphragm member subject to adjustment by suitable control means, as shown in Fig. 1. In operation, the diaphragm is adjusted to apply a force to torsion rod 33 which is slightly less than the force exerted by the air pressure on grid 51 and, as a result, the elements of bearing 53 are kept in operative engagement with each other controlling the axial relationship between the grids.

Another embodiment of the invention provided with a modified mounting for the lower end of the torsion rod is shown in Fig. 5 and comprises a central member 25' having a grid valve and voice coil assembly at the upper end thereof similar in structure to that shown in Fig. 1. Base 25' of said member is threaded into recess 26 of magnet 24 and has a central recess 55 formed therein through which the lower end of torsion rod 33 extends. To mount said rod, a plate 56 is rigidly secured, as by screws 57, to a shoulder 58 formed in magnet 24 beneath recess 26, said plate being held in fluid-tight engagement with said shoulder. To insure fluid tightness, suitable means, such as a gasket (not shown), may be interposed between said shoulder and said plate. Threaded in a recess 59 provided in the center of said plate is a plug 60 having suitable holding means, such as a split chuck mount 61, 62, secured to the lower face thereof for receiving the lower end of rod 33, tapered chuck 61 of said mount being preferably formed with said plug. The end of said rod held by said mount projects beyond the lower end of the latter and can be engaged and adjusted by a suitable tool once nut 62 is loosened.

Another embodiment of the sound head is shown in Fig. 6 wherein a torsion ribbon 63 is substituted for torsion rod 33 of Fig. 5 and suitable means are mounted in plate 56 to operatively secure the lower end of said ribbon. The latter means comprise a plug 64 threaded into recess 59 and provided with an elongated slot 65 conforming substantially to the cross section of said ribbon whereby the latter, when extending through said recess, is held against angular movement. To secure said ribbon against axial movement, a set screw 66 is preferably threaded into the lower end of plug 64 for engagement with the face of said ribbon. By loosening said screw, the tension in ribbon 63 as well as the axial position of grid 29 during operation can be adjusted and by rotating plug 64 angular adjustment of said ribbon and, therefore, of grid 29 can be effected.

There is thus provided a sound head having a novel fluid modulating valve so actuated and mounted as to obtain sound reproduction of a greater fidelity and a greater degree of amplification than has heretofore been possible in sound reproducing devices of the air flow type. There is also provided a novel voice coil and grid assembly whereby vibration transmitting linkages between the magnetically actuated armature and the vibratory member of the valve are eliminated, making possible a faithful reproduction of sound over a wide range of audible frequencies. Novel means for mounting a movable valve member for angular, oscillatory movement in a plane perpendicular to the air stream being modulated thereby are provided, as well as novel means for readily controlling the equilibrium position

of said member. Furthermore, a novel arrangement of ports in the movable and stationary grids of a fluid modulating valve is provided whereby the total fluid passage area of the valve varies directly with the angular displacement of said movable grid from equilibrium position.

Although several embodiments of the present invention have been illustrated and described, it is to be expressly understood that the same is not limited thereto. For example, it will now be apparent to those skilled in the art that holding means other than the conventional split chuck type means shown might be utilized for securing the ends of the torsion rods. Various other changes may be made in the design and arrangement of parts without departing from the spirit and scope of the invention. For a definition of the limits of the invention, reference is primarily had to the appended claims.

What is claimed is:

1. In a sound head wherein a stream of fluid is modulated to generate sound waves, means comprising a passage for said stream, grid valve means interposed in the path of said stream at the discharge end of said passage, said valve means comprising a movable member carrying a disc-like rotary grid, the latter extending across said fluid stream, means for mounting said movable valve member for pivotal movement about the central axis of said grid, said mounting means comprising a torsion member, means for connecting one end of said torsion member to said grid and means for fixing the other end of said torsion member against angular movement, and electro-magnetic means for actuating said movable valve member to modulate the fluid stream, said electro-magnetic means comprising a voice coil wound on said movable valve member and a permanent magnet having the poles thereof disposed diametrically opposite each other and adjacent said valve member.

2. In a sound head wherein a stream of expandable fluid is modulated to generate sound waves, means comprising a passage for said stream, valve means interposed in the path of said stream at one end of said passage, said valve means comprising a stationary grid and a rotary grid member, means for mounting said rotary grid member for movement about an axis parallel to and centrally disposed relative to said stream, said mounting means including a torsion member, means for connecting one end of said torsion member to said rotary grid member and adjustable means for rigidly securing the other end of said torsion member against axial movement, and means for actuating said rotary grid member to modulate the fluid stream, said last-named means comprising a permanent magnet and a voice coil wound on said rotary grid member.

3. In a sound head wherein a stream of fluid is modulated to generate sound waves, means comprising a passage for said stream, grid valve means interposed in the path of said stream at the discharge end of said passage, said valve means comprising a cup-shaped movable member carrying a disc-like grid, means for mounting said movable valve member for pivotal movement about the axis of said grid, said mounting means comprising a torsion ribbon, means for connecting one end of said ribbon to said grid and adjustable means for rigidly securing the other end of said ribbon against movement, and electro-magnetic means directly associated with said movable valve member for actuating the latter to modulate the fluid stream.

4. In a sound head wherein a stream of expandable fluid is modulated to generate sound waves, means comprising a passage for said stream, valve means interposed in the path of said stream at the discharge end of said passage, said valve means comprising a stationary grid and a rotary grid disposed exteriorly of said stationary grid and the discharge end of said passage, means for mounting said rotary grid for angular movement about an axis parallel to and centrally located relative to said stream, said mounting means comprising a bearing carried by said rotary grid and projecting through said stationary grid and having the journal thereof formed in said stationary grid and a torsion member adapted to yieldingly oppose angular movement of said rotary grid from a neutral position, and means for actuating said rotary grid for oscillatory movement to modulate said stream.
5. In a sound head of the type wherein a stream of expandable fluid is modulated to generate sound waves, valve means interposed in the path of the stream, said valve means comprising a circular grid member having a grid portion, means for mounting said grid member for rotary movement about the center thereof in a plane perpendicular to the fluid stream, said means comprising a torsion member adapted to yieldingly oppose movement of said grid member from a neutral angular position, pressure responsive means connecting with said fluid stream and with the atmosphere and fixed to said torsion member; said pressure responsive means tending to move said grid member in a direction opposite to the direction in which the pressure of the fluid stream on the grid portion of said member tends to move it, and means comprising a voice coil carried by said grid member for oscillating the latter to modulate the fluid stream.
6. In a sound head of the type wherein a stream of expandable fluid is modulated, modulating means comprising a rotary grid member having a grid portion, a torsion rod secured to said grid member to oppose movement thereof from a neutral angular position, pressure responsive means connecting with said fluid stream and with the atmosphere and secured to said torsion rod, said pressure responsive means tending to move said grid member axially in a direction opposite to the direction in which the pressure of the fluid stream on the grid portion of said member tends to move it, and electro-magnetic means comprising a voice coil carried by said grid member for oscillating the latter to modulate the fluid stream.
7. In a sound head of the type wherein a stream of expandable fluid is modulated, modulating means comprising a rotary grid member, a torsion means connected to said grid member to oppose movement thereof from a neutral position, electro-magnetic means comprising a voice coil mounted on said grid member, said last-named means being adapted to oscillate said grid member to modulate the fluid stream, and means for adjustably mounting said torsion means to provide a control for the neutral position of said grid member.
8. In a sound head of the type wherein a stream of expandable fluid is modulated, modulating means comprising a rotary grid, a torsion rod secured to said grid to bias the latter to a neutral position, pressure responsive means connecting with said fluid stream and with the atmosphere and secured to said torsion rod, said pressure

responsive means tending to move said grid in a direction opposite to the direction in which the pressure of the fluid stream on the grid tends to move it, and electro-magnetic means for oscillating the grid to modulate the fluid stream.

9. In a sound head, a grid valve for modulating a fluid stream to impart sound producing characteristics thereto comprising a stationary disc-like grid and a grid mounted for oscillatory movement about its center in a plane parallel to said stationary grid, said grids each having tapered slots radially disposed relative to the center of oscillation of the movable grid, said slots all being of the same taper so that the total port area of said valve for fluid passage will 15

vary directly with the angular displacement of said movable grid.
